UNITED STATES PATENT OFFICE

121,058

DESIGN FOR A DIRECTIONAL SIGNAL LAMP

Pliney M. Crone, Kansas City, Mo.

Application February 24, 1940, Serial No. 90,487

Term of patent 14 years

To all whom it may concern:

Be it known that I, Pliney M. Crone, a citizen of the United States and residing at Kansas City, Jackson County, Missouri, have invented a new, original, and ornamental Design for a Directional Signal Lamp, of which the following is a specification, reference being had to the accompanying drawing, forming a part thereof.

In the drawing:

Figure 1 is a side elevational view (the other

side being a duplicate thereof) of a directional signal lamp, showing my new design.

Figure 2 is a top plan view of the same.

Figure 3 is a front elevational view of the same.

Figure 4 is a rear elevational view of the same.

I claim:

The ornamental design for a directional signal lamp as shown and described.

PLINEY M. CRONE.
